PNEUMATIC CANOPY

Filed March 16, 1944

UNITED STATES PATENT OFFICE

2,438,606

PNEUMATIC CANOPY

Charles S. Hulton, Cincinnati, Ohio, assignor to
The Kirk & Blum Manufacturing Company,
Cincinnati, Ohio, a corporation of Ohio

Application March 16, 1944, Serial No. 526,801

7 Claims. (Cl. 98—115)

1

The present invention relates to a canopy or hood for use with industrial installations such as foundry shake-outs which in operation, release air-borne substances that must be removed, and particularly to industrial installations of this class that have presented difficulties due to the method of handling large objects to be operated upon.

An object of the invention is to provide a simple and inexpensive canopy structure that is readily deformable and self-righting so that the canopy offers no serious impediment to the handling of materials or objects by means of a crane hoist. Another object of the invention is to provide a pneumatic canopy which in use projects over a source of air-borne substances in order to enhance the effectiveness of the air exhaust apparatus employed for controlling the released substances. Still another object is to provide a flexible inflated canopy for the indicated purposes which canopy is arranged to facilitate movement of work or material to and from the site of operation while suspending from the chains or cables of a crane hoist.

A still further object of the invention is to provide a pneumatic hood structure which in operation serves to maintain an air pressure area beneath it for retarding the rate of rise of released air-borne substances and thereby subjecting such substances to the operation of the existing air exhaust type collecting means with greatly increased efficiency.

These and other objects are attained by the means described herein and disclosed in the accompanying drawings in which:

Fig. 1 is a side elevational view of a foundry shake-out including an air exhaust apparatus having a pneumatic canopy of the invention mounted thereon.

Fig. 2 is a top plan view of the view of the device of Fig. 1.

Fig. 3 is an enlarged cross sectional view taken on line 3—3 of Fig. 2.

Fig. 4 is a front elevational view of a foundry shake-out installation having modified form of the pneumatic canopy of the invention associated therewith.

Fig. 5 is a cross sectional view taken on line 5—5 of Fig. 4.

It is known in the industrial arts to remove dust, smoke, gases and any other air-borne substances for the purpose of protecting workers, or collecting air-borne substances and for maintaining an atmosphere free of the various air-borne substances. The well-known foundry shake-out is an example of an industrial installation which,

2

in its operation of freeing the foundry flasks of their finished burden, releases dust, gases and smoke, the control of which has been effected to some degree by air exhaust type apparatus disposed alongside the shake-out grate. In those instances where the work is moved to and from the grate by means of traveling crane hoists, it has not been feasible to employ any permanent hood structure overhanging the grate so that excessive power costs and very expensive air exhaust type apparatus have been employed in an endeavor to create a directional air flow across the shake-out grate at a velocity sufficient to carry with it even a reasonable proportion of the liberated substances.

By the present invention the previous difficulties are substantially overcome so that the withdrawal of air-borne substances from the atmosphere in the immediate vicinity of their release is made more complete and is effected at greatly reduced power costs. The present invention consists essentially in disposing above the shake-out grate or point of release of air-borne substances, a canopy that is flexible but self-sustaining, so that it will yield readily in the event of collision of the crane hoist chains or the burden without derogatory effect on the canopy structure. The invention consists further in providing such a flexible canopy structure with a means for discharging air streams in opposition to the normal stack draft conditions of the room and to thus afford a sort of air blanket which confines the substances to be removed to the relatively restricted space in which air exhaust type removal apparatus is most effective.

Referring now to the drawings, it will be noted in Fig. 1 that the casing 10 forms part of an exhausting device such as a dust collector apparatus and shake-out 11 is disposed immediately alongside the shake-out. Shake-out 11 has a grate 12 across which air is caused to travel at a suitable velocity through controlled openings in a baffle 13 into an equalizing plenum chamber 14 from whence the air is exhausted at a sufficient rate by any suitable means. In applying the canopy of the present invention to the hereinbefore referred to exhausting structure, it is necessary only to provide a simple air pressure chamber 15 which consists of a rigid box-like structure disposed atop of the casing 10. A suitable low capacity blower or fan structure 16 is arranged to provide a relatively constant volume of pressure air to the chamber 15, the air intake being in this case supplied through pipe 17 which may communicate with the exterior of the building. Chamber 15 is provided on its forward vertical

side by a suitable surrounding flange 18. The flange 18 receives the mouth of a large flexible envelope constituting the body of canopy 19 which may be of canvas or other more fire-resistant fabric such as the asbestos and glass fiber fabrics now known and available in the markets. The mouth of envelope 19 is rectangular to snugly fit flange 18 and a binding strap 20 serves to secure the mouth of the envelope over the open side of pressure chamber 15. In its preferred form the envelope comprising canopy 19 is formed at its forward edge into a plurality of hollow tubular fingers 21. In order to sustain the rearward portion of the envelope against undue bulging, the top and bottom walls of the envelope are connected by fabric strips or gussets 22 which are aligned with the junctions of the fingers 21 (see Fig. 3). Upon inflation of the envelope the adjacent fingers assume substantial contact with each other and the rear portion of the envelope assumes a wide flattened shape, the thickness of which is substantially limited by the interiorly connected fabric gussets. In the forward lower portion of each of the fingers 21 there is provided at least one restricted port or opening 23 which may be suitably reinforced by a grommet 24.

In use, the air exhauster apparatus is set into operation for creating a velocity air flow in the direction of the arrows 25 and passing through the equalizing plenum chamber 14 and in the direction of arrow 26 through pipe 27. With blower apparatus 16 in operation the envelope 22 becomes inflated and assumes the substantially horizontal position as shown in Figs. 1, 2, and 3, and also discharges streams of air indicated at 28 in a downwardly direction beneath the hood. The effect of air streams 28 is to oppose the normally upward movement of air and it sets up a blanket of pressure air in opposition to the natural tendency of the heat, dust and smoke to rise from the shake-out. This not only prevents the dust, smoke and the like from escaping into the free atmosphere, but tends to increase the effectiveness of the air stream 26 so that considerably lesser power costs are involved in maintaining a sufficient velocity of the air stream 25 to collect the released airborne substances from the vicinity of the shake-out grate. It is to be understood that the capacity of fan or blower apparatus 16 need not be great in order to maintain a sufficient air pressure within the envelope 19 to sustain the latter in the outstretched condition as shown. The canopy 19 may be extended to and beyond the center of the surface of grate 12 so that should the cable or chain 29 which supports the flasks 30 in moving the latter to and from the grate may encounter the canopy without injury to the latter. The spaces 31 between adjacent fingers 21 of the canopy provide for the passage of cable or chain 29 without any deformation whatsoever of the canopy. Likewise should one of such fingers 21 be collapsed by the cable during entry of the burden to the grate, then the shifting of the cable will enable the pneumatic finger 21 to readjust itself to substantially normal outstretched position.

When the shake-out apparatus is shut down and out of use, the canopy 19 would be deflated because fan 16 would be at rest and the canopy would hang down as a limp envelope over the front opening of casing 10.

In Figs. 4 and 5 there is shown a modified structure wherein the casing 100, corresponding

generally to the casing 10 of Fig. 1, has mounted on the upper portion thereof an inverted substantially U-shaped pressure chamber 32 with a suitably driven fan or blower 160 mounted on the top thereof. The canopy 190 has its rear edge secured in open communication with the U-shaped outlet side of chamber 32 in any suitable manner, for example as described in connection with Figs. 1-3 inclusive. Canopy 190 has depending side walls 33 and the entire canopy structure is preferably provided with tubular fingers 34 on the forward edge thereof. As is best illustrated in Fig. 4, the depending side walls 33 assist in confining an area above the shake-out 11. An intake chamber 35 is interposed between casing 100 and the pressure chamber 32 so that the intake port 36 is disposed directly beneath the canopy. By means of this structure there is attained a recirculation of air which is utilized to keep the canopy inflated and in a self-sustaining position. The flow of velocity air which passes through the ports in baffle 130 is taken into the equalizing plenum chamber 140 and thence through pipe 270. In operation the blower 160 produces the desired volume of pressure air to inflate the envelope comprising the canopy 190 and the downwardly directed streams of pressure air from the openings 230 maintain a pressure air body around the work such as flasks 30 in order to oppose the spread of liberated dust, smoke and the like to the surrounding atmosphere. It will be further understood that the air streams from ports 230 also tend to set up a flow of air from the surrounding atmosphere inwardly through the spaces between the fingers 34.

It will be understood that the recirculation of the inflating pressure air is effected at a somewhat lesser power cost than in drawing the air from the exterior of a building for example as by pipe 17 as shown in Fig. 1. At least a proportionate increase in efficiency of the air exhauster apparatus 100 is gained by the cooperative relationship of the parts as shown in Fig. 5.

It will be understood that the use of the depending side walls 33 may be eliminated if desired in a construction as typified in Figs. 4 and 5, and that a structure as exemplified in Figs. 1 and 2 may be modified within the scope of this invention, by the addition of such canopy side walls.

In general the costs involved in the construction of a canopy of a class herein described and in the operation of the inflating means is comparatively small, particularly in view of the great increase in efficiency of the collecting capacity of the removal apparatus employed. There is a further gain represented in the speed with which the work may be brought to and removed from the shake-out because the danger of damage to the canopy is completely eliminated.

It will be understood that the envelope 19 forming the canopy may be constructed completely of individual cylindrical finger members secured directly to a pressure chamber 15, such a construction serving to afford a somewhat greater degree of flexibility to the structure in use. Such an arrangement of independent cylindrical fingers in side by side relation throughout the depth of the canopy will obviously facilitate the replacement of any individual finger in the event it becomes worn out, punctured or torn due to some unusual occurrence.

What is claimed is:

1. In an air exhauster type collection appara-

tus the combination of a casing having an intake opening in a vertical side wall thereof, means connected with the casing for drawing in air and dust through said opening, an air pressure supply chamber mounted on the casing and having an outlet in a vertical plane disposed above said inlet opening in said casing and a flexible inflatable envelope connected at its rear edge with the air pressure chamber and communicating interiorly with the air outlet in said chamber, and means supplying pressure air to said chamber, whereby the envelope is maintained in an inflated condition and extends horizontally to form a canopy over a substantial area adjacent and communicating with said intake opening in the casing.

2. A canopy of the class described comprising side by side tubular portions each closed at a common end and open on the opposite end, a relatively flat hollow flexible fabric body secured to and in open communication with the open ends of said tubular portions, each being in substantial contact with adjacent tubular portions and said tubular portions having restricted vent ports in the bottoms thereof, means for securing said body to a vertical side wall and means for continuously supplying air under pressure to said envelope for filling the envelope and yieldably projecting in a horizontally extended relation to the supporting side wall.

3. In a self-positioning canopy structure, the combination of a flexible fabric envelope having one open edge and the remaining edges closed, means for securing said open edge to a vertical wall and means for constantly introducing air under pressure into the opened and attached edge of the envelope for maintaining said envelope in a pressure filled distended and horizontally extending condition.

4. A foundry shake-out installation comprising a shake-out including a grate, air exhaust type collecting apparatus including a casing disposed in upright position alongside said shake-out end having an inlet opening on the side adjacent said shake-out, a flexible hollow envelope rigidly secured horizontally along one side thereof to said casing above said inlet opening and means for supplying pressure air into said envelope at its said rigidly secured side whereby said envelope is inflated and distended and yieldably maintains a projecting position overhanging a substantial area of the grate.

5. In an air exhaust type collection apparatus the combination of a casing including a vertical side wall having an intake opening therein and defining one side of an extended work area requiring substantially unimpeded access from its remaining sides, means connected with the casing for drawing in air and dust through said opening, an air pressure supply chamber mounted on top of the casing and substantially within the body lines thereof, said chamber having an independent, transverse air pressure outlet closely above the top of said intake opening in the casing, a flexible fabric, flat envelope of width corresponding to the width of the work area and of length corresponding to a substantial portion of the length of said work area, said envelope having an opening along its rear edge, means securing the sides of said opening about the air pressure outlet in said chamber for establishing communication with the interior of the envelope, means providing a pressure air supply to said chamber and flexible means secured at opposite edges to the interior top and bottom of the en-

velope for limiting the distention of the envelope in the direction of its thickness only under the influence of said pressure air whereby said envelope under continuous air pressure assumes a self-sustaining, horizontal roof-like position over a substantial portion of the work area adjacent the casing.

6. In an air exhaust type collection apparatus the combination of a casing including a vertical side wall having a suction intake opening therein, means connected with the casing for drawing in air and dust through said opening, an air pressure supply chamber mounted on the casing and having a transverse pressure outlet opening at least co-extensive with said collection intake opening in the casing and in substantially the same plane therewith, a substantially flat, flexible fabric envelope having an opening at its rear edge only, means securing the envelope to said pressure supply chamber with the opening in the envelope communicating with the opening in said chamber, said envelope being of substantial length and breadth, flexible members connected at their opposite ends to the opposed, inner major faces of the envelope for limiting separation thereof, and means providing a constant supply of pressure air to said chamber for maintaining the envelope in a distended, flattened and substantially horizontal, roof-like position above the top of said intake opening in the casing and over a substantial portion of the area immediately adjacent whereby airborne substances released in said work area are substantially precluded from movement out of the zone of suction of said intake opening.

7. A canopy of the class described comprising a relatively flat hollow flexible body, means to rigidly mount the rear edge of said body on a vertical supporting surface, means to introduce air under pressure into said hollow body at said rear edge for inflating said body and pneumatically sustaining it at substantially right angles to the vertical supporting surface, a series of integral tubular fingers extending outwardly from the forward edge of said body, said fingers being closed at their free ends and individually in communication with the interior of the body at the forward edge of said body, said fingers each contacting adjacent fingers whereby said fingers form a composite and sectionally deformable forward extension on said body, and gusset members secured in spaced relation across the interior of said body and limiting the expansion thereof under pneumatic pressure to substantial conformity with the series of hollow fingers.
